Term of patent 14 years

Int. Cl. D13—02

U.S. Cl. D55—1 R

FIG. 1 is a perspective view of the top, end and one side of the transformer pad or the like showing my new design; and

FIG. 2 is a perspective view of the bottom, end and opposite side thereof.

The end opposite to that shown in FIGS. 1 and 2 of the drawing is substantially a mirror image of the end shown therein.

This is a continuation-in-part of my design application, Ser. No. 412,511, filed Nov. 2, 1973, and now abandoned. I claim:

The ornamental design for a transformer pad or the like, as shown and described.
